TILTING MECHANISM FOR VENETIAN BLINDS

Julius Nisenson, Brooklyn, N. Y., assignor to Master Venetian Blind Hardware Corp., New York, N. Y., a corporation of New York

Application May 17, 1937, Serial No. 143,060

19 Claims. (Cl. 156—17)

This invention relates generally to Venetian blind head-rail, head-bar, or casing construction, and more particularly to tilting mechanism for tilting the slats of the blind.

5 Among the objects of the present invention is the provision of a unitary tilting mechanism which is interchangeable in use so that the same may be utilized with either an exposed head-bar and tilt-bar or with a casing having concealed tilt plates.

10 The present invention is especially suited for use in combination with a channel casing as for example that described in Patent Number 2,036,231, granted to me on April 7, 1936. Such use will be more fully set forth below.

15 Another object of this invention is the provision of a tilting mechanism which is readily actuated either by cord or bead chain, and where the mechanism is included in an enclosed casing the cord or chain may be simply adjusted from outside of the casing.

20 A further object herein is the provision of a structure which is simple, light in weight, strong, efficient, and foolproof in operation.

25 A still further object is the provision of a tilting mechanism requiring a minimum of parts, which are either stampings or automatic screw machine products, and which require a minimum of labor and expense to assemble.

30 These objects, further features, and incidental ends and advantages will more fully appear in the progress of this disclosure and as pointed out in the appended claims.

In the accompanying drawings, similar reference characters designate corresponding parts throughout the several views in which:

35 Figure 1 is a fragmentary plan view of one end of a channel casing such as shown in the patent identified hereinabove, the casing containing one form of tilting mechanism embodying the present invention.

40 Figure 2 is a front elevational view of Figure 1 partly broken away to show concealed parts.

45 Figure 3 is an end elevational view of Figure 2 as seen from the left end thereof.

Figure 4 is a rear elevational view of the tilting mechanism removed from the Venetian blind casing and viewed from the left of Figure 3.

50 Figure 5 is an enlarged sectional view partly in elevation as seen from the plane 5—5 on Figure 4.

Figure 6 is a vertical sectional view of the form of the tilting mechanism shown in Figure 4 as seen from the plane 6—6 on Figure 5.

55 Figure 7 is a developed view of the frame plate.

Figure 8 is a fragmentary sectional view partly in elevation of an alternate means for mounting the gear.

Figure 9 is a fragmentary elevational view as seen from the right of Figure 8 with the gear casing plate removed showing the tilting shaft, gear hub, and gear.

Figure 10 is a fragmentary view of the tilting mechanism as adapted for use on an exposed head-bar and attached to an exposed tilt-bar, as seen in front elevation.

Figure 11 is an enlarged perspective view of the bracket which connects the tilt bar with the gear hub.

The tilting mechanism, generally represented by numeral 10, is cased in a housing 11 composed of gear casing plates 12 and 13 and a frame plate 55.

A gear 15 is provided with a central orifice 16 which is shaped to conform to the hub 17 having a flattened portion 18. Gear 15 is mounted upon hub 17.

The hub 17 is trunnioned in circular orifices 19 and 20 in the gear casing plates 12 and 13 respectively, and is retained in position by the shoulder or integral collar thereon 21 and a snap-on split washer 22 which engages an annular groove 23. Hub 17 is provided with a central orifice 24 in which is located a shaft 25 maintained in position by a set screw 26. The shaft 25 is shown as broken off but it is to be understood that shaft 25 continues to connect with and to actuate any suitable means (not shown) for tilting the slats of a Venetian blind, such as the tilt-plates described and shown in my patent referred to above.

A worm shaft 27 has integral therewith a narrow shoulder 28, a wide shoulder 29, a pin 30, and a milled or roughened portion 31. Shaft 27 carries mounted thereon a worm 32 and is journaled in a front bearing 33 and a rear bearing 34 having external annular flanges 35 and 36 respectively. Flanges 35 and 36 are preferably rectangular in cross section.

The pin 30 has mounted thereon a pair of opposed concave discs 37 and 38 which have corrugations or flutes 39 and 40. The discs 37 and 38 have the central portions thereof forced into close contact by swaging over the terminal 41 of pin 30 thereby forming the cord or chain pulley 42. In order to fix the position of pulley 42 with relation to pin 30 and hence the shaft 27, the pin 30 may have a flattened portion corresponding with the flattened portion 18 on hub 55.

17 and the discs 37 and 38 may be orificed similarly to the gear 15.

The gear casing plates 12 and 13 are identical and symmetrical so that they are completely interchangeable. These casing plates 12 and 13 include circular gear recesses 43 and 44, front bearing pockets 45 and 46, worm pockets 47 and 48, rear bearing pockets 49 and 50 respectively and all located in the vertical portions thereof. Casing plates 12 and 13 have horizontal portions or feet 51 and 52 respectively which are disposed at right angles to the vertical portions thereof. Feet 51 and 52 are provided with internally threaded holes 53 and 54 respectively. The bearing pockets 45, 46, 49, and 50 are shaped on the inner surfaces thereof to conform to the outer surfaces of the bearings 33 and 34 and the flanges 35 and 36 so that a close fit is obtained and when the casing plates 12 and 13 are assembled the said bearings are maintained in proper operating position with the axes thereof aligned and with the bearings prevented from turning. The flanges 35 and 36 are seated in corresponding depressions in the bearing pockets 25 and the bearings are thereby prevented from shifting toward or away from each other longitudinally with relation to shaft 27.

The worm pockets 47 and 48 are sufficiently large to completely clear the worm 32. All of the pockets both worm and bearing are so located on the gear casing plates with relation to orifices 19 and 20, that the worm 32 makes a satisfactory mesh with the gear 15.

A frame plate 55 is comprised of a vertical front portion 56 with an integral lug 57, a horizontal base 58 having a rectangular orifice 59, and a connecting plate portion 60 having a rectangular orifice 61 and circular orifices 62 and 63. The horizontal base 58 is cut along the solid lines 64 to form two cord or chain guide tabs 65 and 66 which cooperate with the pulley 42 as will be more fully described below. The tabs 65 are integral with the base 58 and are bent upwardly therefrom to take a form best seen in Figure 4 of the accompanying drawings. The connecting plate portion 60 is upwardly offset by bending the frame plate 55 at 67, indicated on Figure 7 by dot-dash lines. The amount of offset of plate portion 60 is equal to the thickness of the feet 51 and 52. The orifices 61 and 62 are preferably wide enough to permit the screws 68 and 69 to penetrate freely therethrough. The dimensions of the rectangular orifice 61 are governed by the width of the feet 51 and 52 and the manner in which the pockets 47 and 48 are formed in the gear casing plates 12 and 13. The more completely the pockets 47 and 48 encircle the worm 32, the narrower may be the orifice 61 as viewed in Figure 7. The relative dimensions shown in Figure 6 have been found satisfactory since the large opening facilitates the assembly of the parts.

The assembly of the various components into a complete mechanism is a simple and rapid procedure. The following method has been found satisfactory. The worm shaft 27 with the pulley 42 affixed as described above is grasped and the bearing 33 is slid into place against the wide shoulder 29; followed by the worm 32 which is forced into place on the roughened portion 31 until it abuts the narrow shoulder 28 and the inner portion 70 of bearing 33; then follows the bearing 34 which is slid on the shaft.

The gear casing plate 13 is grasped and the hub 17 is inserted into the orifice 20. The gear

15 is then placed upon the hub with the orifice 16 properly engaging the flattened portion 18. The foot 52 is then inserted through the orifice 61 of frame plate 55. Next the shaft 27 as previously assembled is placed upon the gear casing plate 13 and the bearings 33 and 34 properly seated in the pockets 46 and 50, the worm 32 is meshed with the gear 15, and the pulley 42 is placed partially in orifice 59. The gear casing plate 12 is placed into position by inserting the foot 51 through the orifice 61 in the frame plate 55 and moving the upper portion of said plate toward the corresponding upper portion of plate 13, at the same time inserting the hub 17 through the orifice 19 in plate 12. Snapping the split washer 22 onto the groove 23 and riveting the plates 12 and 13 together at the upper corners thereof by rivets 71 in the holes 72, completes the assembly.

In the drawings the groove 23 is placed with relation to the collar 21 so as to allow considerable clearance. The position of this groove may be changed as desired, and if the groove is moved considerably toward the said collar and a heavy split washer is used, sufficient compression may be obtained between plates 12 and 13 so that the rivets 71 may be dispensed with.

The complete assembly or mechanism 10 is preferably installed within a casing 73 by means of the screws 68 and 69 which penetrate suitable orifices in the bottom wall 74. The mechanism 10 is positioned within casing 73 so that the front portion 56 and the front wall 75 of the casing 73 are spaced and parallel, the spacing being sufficient to allow a movable latching plate 76 to slide horizontally therebetween. This latch plate 76 is provided with a manual gripping tab 77, and an inwardly upset lug 78 riding just above the upper edge of portion 56. The lug 57 is thus adapted to act as a stop to prevent the latching plate 76 from being pulled too far out of the casing 73. The structure and functions of latching plate 76 are more particularly described in my patent identified above. The bottom wall 74 is provided with a suitable orifice (not shown) through which a cord or the chain 79 passes as it approaches or leaves the pulley 42.

Figures 8, 9, 10, and 11 illustrate an alternative embodiment of a portion of the invention. In this form, the hub 80 is made from a piece of 50 square rod stock which has been turned down, preferably in an automatic screw machine to leave the square corners 81 and the rounded corners 82. The corners 81 are preferably as wide as the gear 83 which is provided with a central square orifice so that said gear 83 is positively keyed to the hub 80 merely by being placed thereon. The distance from one rounded corner 82 to another diametrically opposite thereto is preferably equal to the diameter of the orifices 19 and 20 in the plates 12 and 13. It may thus be seen that the square corners 81 serve to connect with the gear 83 and prevent the hub 80 from coming out of the chamber formed by the circular gear recesses 43 and 44.

This alternate structure of the hub is especially suited for use in connection with exposed head-bar and tilt-bar Venetian blinds. Turning to Figure 10 there is seen an embodiment of the invention as adapted for such use in which the head bar 84 carries the alternate form of tilting mechanism 85 which supports the tilt-bar 86 by means of a novel bracket 87. This bracket is shown in Figure 11, and comprises a large horizontal portion 88, a short vertical portion 89, a 75

short horizontal portion 90, and a large vertical portion 91 having a square hole 92. The portion 88 is adapted for suitable attachment to the tilt-bar 86 as for example by wood screws. The

5 portion 89 serves as a stop to simply and accurately space the tilt-bar 86 with relation to the mechanism 85. The square hole 92 is adapted to fit the square hub 80 and need only be slipped thereon to secure positive connection between the bracket 87 and the hub. Because the square hole 92 is slightly oversize a partial "universal joint" 10 type of connection is secured and the assembly of the head-bar 84 is facilitated in that the mechanism 85 need not be accurately lined up. 15 Further a four sided hub 80 requires at the most only a 90 degree rotation thereof in order to take on a position coinciding with any rotated position of the tilt-bar 86 and bracket 87.

When the alternate mechanism 85 is installed 20 on an exposed head-bar 84, there is no need for the vertical front portion 56 and the lug 57 and these parts may be dispensed with. The mechanism 85 may then be conveniently attached to the head-bar 84 for example by inserting wood 25 screws 93 through the internally threaded orifices 53 and 54 in feet 51 and 52 and orifices 62 and 63. It is understood of course that the mechanism 85 is thus in an inverted position with relation to the position of mechanism 10.

30 With regard to the hub 80, this may be provided with an orifice 94 (see Figure 8) which corresponds to the orifice 24, and a set screw 95. In this manner a single assembly or tilting mechanism may be had which is equally suitable for use 35 with a shaft such as shaft 25 or a bracket such as bracket 87.

The pulley 42 is of novel construction in that the flutes 39 and 40 are directly opposite each other and are relatively sharp on the inside faces 40 thereof. The flutes are thus adapted to prevent the slipping of the bead chain 79 since each of the beads falls between said flutes. Cord may also be used on the same pulley and the flutes serve to grip the cord so that slippage is considerably 45 reduced.

The guide tabs 65 and 66 are so positioned with relation to the pulley 42 that by pushing upwardly on the portions of a cord or the chain 79 exposed outside of the casing 73, the cord or chain 50 may be disengaged from the pulley to form a loop thereabove and the position of the cord or chain may be changed independently of the pulley. After the position has been changed, pulling the 55 two exposed portions of the cord or chain will seat the same in the pulley groove.

Since the length of the bearing 33 including the portion 70 thereof is equal to the normal spacing between the worm 32 and wide shoulder 29 when the flange 35 is properly seated in the bearing 60 pockets 45 and 46, the worm shaft 27 is prevented from longitudinal displacement and the thrust of the worm 32 is taken by the ends of bearing 33. This construction also maintains the pulley 42 in a properly centered position in the orifice 59 so that it rotates without touching the adjacent structure.

It may now be seen that there has been provided a simple and efficient tilting mechanism for Venetian blinds which is suitable for use 70 with channel type enclosed head bars and exposed head bars, and that the same is compact, sturdy, foolproof and inexpensive.

The foregoing disclosure is to be regarded as descriptive and illustrative only, and not as restrictive or limitative of the invention, of which

obviously an embodiment may be constructed including modifications without departing from the general scope herein indicated and denoted in the appended claims.

Having thus described my invention, what I 5 claim as new and desire to secure by Letters Patent, is:

1. A Venetian blind tilting mechanism including: a casing having aligned orifices therein; a hub journalled in said orifices; a gear mounted 10 on said hub and keyed thereto so that the gear rotates therewith, said gear being free to move longitudinally on said hub but restrained in such longitudinal movement by said casing.

2. A Venetian blind tilting mechanism including: a casing having coaxially aligned orifices therein; a hub having a periphery, non-circular in cross section and trunnioned in said orifices; a gear mounted on said hub and keyed thereto so that the gear rotates therewith, said gear being 20 free to move longitudinally on said hub but restrained in such longitudinal movement by said casing.

3. A Venetian blind tilting mechanism including: a casing composed of two plates, a foot on 25 each plate, means connecting said feet, said plates being oppositely disposed and having coaxially aligned orifices therein; a hub journalled in said orifices; a gear mounted on said hub and keyed thereto so that the gear rotates therewith, said 30 gear being free to move longitudinally on said hub but restrained in such longitudinal movement by said casing.

4. A Venetian blind tilting mechanism including: a casing having coaxially aligned orifices 35 therein; a hub, having a certain external non-circular cross section and trunnioned in the orifices in said casing; a gear having an orifice of substantially the same configuration as the cross section of the hub and being mounted on said hub 40 so that the gear is loosely keyed thereto; and a worm meshing with said gear and rotatably mounted in said casing.

5. A Venetian blind mechanism for tilting the slats including: a housing composed of two casing plates; a foot on each casing plate; a connecting plate having an orifice within which the feet of the casing plates are engaged and whereby the portions of said casing plates adjacent the connecting plate are held in operative position.

6. A Venetian blind tilting mechanism including: a housing composed of two casing plates; a foot on each casing plate; a connecting plate having an orifice within which the feet of the casing plates are engaged and whereby the portions of said casing plates adjacent the connecting plate are held in operative position; and means in addition to said connecting plate for maintaining the casing plates together to form a housing, said means being disposed on the free 60 ends of said casing plates.

7. A Venetian blind tilting mechanism including: a housing composed of two casing plates; a foot on each casing plate which is an integral bent tab; a connecting plate having a rectangular orifice within which the feet of the casing plates are engaged and whereby the portions of said casing plates adjacent the connecting plate are held in operative position; and rivets disposed adjacent the free ends of said casing plates 70 for maintaining the casing plates together to form a housing.

8. A Venetian blind tilting mechanism including: a housing composed of two casing plates; a worm mounted on a shaft; a trunnioning means 75

on said casing plates forming bearing supports for said shaft when the casing plates are brought together; a foot on each casing plate disposed on one side of said means; a connecting plate 5 having an orifice within which the feet of the casing plates are engaged and whereby the portions of said casing plates adjacent the connecting plate are held in operative position.

9. A Venetian blind tilting mechanism including: a housing composed of two casing plates; a worm mounted on a shaft; trunnioning means on said casing plates forming bearing supports for said shaft when the casing plates are brought together; a foot on each casing plate disposed 10 to one side of said trunnioning means; a connecting plate having an orifice within which the feet of the casing plate are engaged and whereby portions of said casing plates adjacent the connecting plate are held in operative position; and 15 second means for maintaining the casing plates in operative position, said second means being disposed on the other side of the trunnioning means.

10. A Venetian blind tilting mechanism including a housing composed of two casing plates which have bearing receiving pockets; a pair of bearings disposed within said pockets; a worm mounted on a shaft which is journaled in said bearings; said bearings being maintained in position 20 when the casing plates are brought together; a foot on each casing plate disposed to one side of the bearing pockets; a connecting plate having an orifice within which the feet of the casing plates are engaged and whereby portions 25 of said casing plates adjacent the connecting plate are held in operative position.

11. A Venetian blind tilting mechanism including a housing composed of two casing plates which have bearing receiving pockets; a pair of 30 bearings disposed within said pockets; a worm mounted on a shaft which is journaled in said bearings; said bearings being maintained in position when the casing plates are brought together; a foot on each casing plate disposed to one side 35 of the bearing pockets; a connecting plate having an orifice within which the feet of the casing plates are engaged and whereby portions of said casing plates adjacent the connecting plate are held in operative position; and second means for maintaining the casing plates in operative position, said second means being disposed on the other side of the bearing pockets and serving in addition to securely clamp the bearings between the bearing plates.

12. A Venetian blind tilting mechanism including: a housing composed of two casing plates, each of said casing plates being constructed of sheet material and having a gear recess stamped therein and an orifice in the gear recess; a gear 40 trunnioned in said orifices; a worm engaging said gear and mounted on a shaft; trunnioning means on said casing plates forming bearing supports for said shaft when the casing plates are brought together; a foot on each casing plate to one side 45 of said means; and a connecting plate having an orifice within which the feet of the casing plates are engaged and whereby portions of said casing plates adjacent the connecting plate are held in operative position.

13. A Venetian blind tilting mechanism including: a housing composed of two casing plates, each of said casing plates being formed from sheet material and having a gear recess pressed 50 therein and an orifice in the gear recess; a gear trunnioned in said orifices; a worm engaging the

gear and mounted on a shaft; trunnioning means on said casing plates forming bearing supports for said shaft when the casing plates are brought together; a foot on each casing plate to one side 5 of said means; a connecting plate having an orifice within which the feet of the casing plates are engaged whereby portions of said casing plates adjacent the connecting plate are held in operative position; and second means for maintaining the casing plates in operative position, 10 said second means being remotely positioned with relation to said connecting plate.

14. A Venetian blind tilting mechanism including: a housing composed of two casing plates, each of said casing plates being formed from sheet material and having a gear recess therein, and an orifice in the gear recess; a gear trunnioned in said orifices; a worm engaging said gear and mounted on a shaft; trunnioning means on said casing plates forming bearing supports 15 for said shaft when the casing plates are brought together; a foot on each casing plate to one side of said trunnioning means and having an orifice; a connecting plate having an orifice within which the feet of the casing plates are engaged and whereby portions of said casing plates adjacent the connecting plate are held in operative position, and whereby the orifices in the feet are adapted for use in connecting the mechanism to a Venetian blind headbar.

15. A Venetian blind tilting mechanism for use with a cord or chain including: a housing composed of two casing plates, each of said casing plates being formed from sheet material and having a gear recess pressed thereon and an orifice in the gear recess; a gear trunnioned in the said orifices; a worm engaging said gear and mounted upon a shaft; a pulley affixed to said shaft; trunnioning means on said casing plates forming bearing supports for said shaft with the pulley disposed outside of the housing when the casing plates are brought together; a foot on each casing plate to one side of said means; a connecting plate having a connecting opening and a guide opening, said feet being engaged in the connecting opening and said pulley being disposed adjacent said guide opening; and a pair of bent integral guide tabs formed from the connecting plate portions bordering the guide opening, whereby a chain or cord may be guided into 50 engagement with said pulley.

16. A Venetian blind tilting mechanism including: a housing composed of two casing plates oppositely disposed and having coaxially aligned orifices therein; a hub having a central portion with outwardly extending projections thereon and therefore being non-circular in cross section and larger in diameter than said orifices, said hub having end portions which are reduced in diameter and non-circular in cross section 55 and whose greatest diameter is less than the diameter of either of said orifices; a gear disposed within the housing and having an orifice corresponding in shape to the central portion of the hub and being mounted thereon; whereby the gear is keyed to the hub and rotates therewith, said gear being free to move longitudinally on said hub but restrained in such longitudinal movement by said casing.

17. A Venetian blind tilting mechanism including: a housing composed of two casing plates oppositely disposed and having coaxially aligned orifices therein; a hub having a central portion with projections thereon and therefore being non-circular in cross section and larger in diameter 70 and

than said orifices, said hub having end portions which are reduced in diameter and non-circular in cross section and whose greatest diameter is less than the diameter of either of said orifices; a gear disposed within the housing and having an orifice corresponding in shape to the central portion of the hub and being mounted thereon; whereby the gear is keyed to the hub and rotates therewith, said gear being free to move longitudinally on said hub but restrained in such longitudinal movement by said casing; and a tilting bar bracket having a portion thereof adapted for attachment to a tilting bar and having another portion with an orifice corresponding in shape to an end portion of said hub, whereby the bracket may be rotatably keyed to the said end portion of the hub but slidable therealong.

18. A Venetian blind tilting mechanism including: a housing composed of two identical casing plates oppositely disposed and having coaxially aligned orifices therein; a hub journaled at its ends in said orifices, and polygonal in cross section; the polygonal corners on each of the hub ends connecting the sides being rounded a substantial distance in from the said hub ends, the hub thus having a central portion with the polygonal corners intact forming outwardly extending projections thereon, the diameter of the central portion of the hub between any two opposite polygonal corners being greater than the

orifices in the casing plates; the hub thus having hub ends with rounded polygonal corners acting as bearing surfaces in cooperation with said orifices, the diameter of the hub ends between any two opposite rounded polygonal corners being less than the diameter of the orifices in the casing plates; a gear disposed within the housing and having an orifice corresponding in shape to the central portion of the hub and being loosely mounted thereon; whereby the gear is keyed to the hub and rotates therewith, said gear being free to move longitudinally of the hub; the gear and central portion of the hub being independently restrained in such longitudinal movement by the said casing.

19. A Venetian blind tilting mechanism including: a housing composed of two casing plates; a worm mounted on a shaft; a bearing having a peripheral flange rotatable on said shaft and fixed in position by being compressed between corresponding depressions in said casing plates; a foot on each casing plate disposed on one side of said means; a connecting plate having an orifice within which the feet of the casing plates are engaged and whereby the portions of said casing plates adjacent the connecting plate are held in operative position to compress the said bearing in the said plates.

JULIUS NISENSON.
